UNITED STATES PATENT OFFICE.

WILLIAM A. SHARPE, OF DENVER, COLORADO.

ELECTROLYTIC SEPARATOR.

Application filed April 29, 1922, Serial No. 557,288. Renewed October 30, 1923.

To all whom it may concern:

Be it known that I, WILLIAM A. SHARPE, a citizen of the United States, residing at the city and county of Denver and State of Colorado, have invented certain new and useful Improvements in Electrolytic Separators; and I do declare the following to be a full, clear, and exact description of the invention, such as will enable others skilled 5 in the art to which it appertains to make and use the same, reference being had to the accompanying drawings, and to the characters of reference marked thereon, which form a part of this specification.

10 This invention relates to an apparatus for the separation of metals from pulverized ores by electrochemical and electromagnetic means.

It is the object of this invention to produce a machine by means of which the metals can be readily and completely separated from the ground or powdered ores by passing the ore through a succession of separate vats, each of which contains an 20 electrolyte that will cooperate with one or more of the metals present, and to deposit the metal, electrolytically, on a rotating metal cylinder.

It is well known that a chemical compound can be separated into its constituents by means of an electric current, and that the metallic ions in an electrolyte through 30 which a current passes will travel from the anode to the cathode and be deposited in the form of metal on the cathode surface. This has been taken advantage of in the well known processes of electroplating and electrometallurgy in general.

In separating the metals from the non-metallic portions of the ores, I have recourse to the well known method of electrolysis. I have devised a machine in which the ore in its pulverized state is deposited on an endless belt of flexible insulating material, 40 such as rubber, whose upper surface has secured thereto a plurality of carbon rods placed side by side so as to form a continuous surface upon which the ore rests. The carbon surface is electrically connected to the positive pole of a suitable source of direct current. A plurality of rotating cylinders are placed above the upper surface of the conveyor belt and are electrically connected to the negative pole of the source

of current, thus forming the cathode. The 55 belt is spaced from the surface of the cathode cylinders by means of idlers, and the anode and cathode surfaces are substantially concentric for about 120 degrees or more when the belt bends reversely over 60 another set of idlers and forms another depression underneath a second cathode cylinder. A tank or vat is provided beneath each cathode and contains a suitable electrolyte within which the anode and cathode 65 move. As many separate cathodes as desired may be used and the ore carried from one cell to the other on the continuous belt anode, all as will herein be more fully described by reference to the accompanying 70 drawing in which—

Fig. 1 is a front elevation of my improved electrolytic ore separator;

Fig. 2 is a longitudinal vertical section thereof;

Fig. 3 is a rear elevation of my separator;

Fig. 4 is a transverse section taken on line 4—4, Fig. 3;

Fig. 5 is a section similar to Fig. 4, but showing a modification;

Fig. 6 is a longitudinal section of the belt; and

Fig. 7 is a detail showing the groove in the outer surface of the cylindrical cathode.

The same reference numerals will be used 85 to designate the same parts throughout the several views.

My machine consists of a framework having longitudinal side timbers 1 and 2, which is supported on suitable legs 3. Sides 4 and 5 are secured to the inner side of side pieces 1 and 2 and the legs 3, and these form the ends of a series of transverse tanks 6, 7 and 8, which are separated from each other by upwardly extending inclined sides 9, in the manner clearly shown in Fig. 2. Tanks 6, 7 and 8 are designed to contain the electrolyte which is employed in carrying out the process which will hereinafter be explained. Rotatably mounted in suitable bearings 10 near the right hand end of the machine is a shaft 11 upon which is mounted a pulley 12, which serves as the driving means whereby motion is transmitted to the endless belt 13. At the other end of the machine I provide a guide slot 14 on each side and slidably mounted in each slot is a bearing 15 which can be adjusted by means of a screw

16 having a handwheel 17. A shaft 18 is rotatably mounted in bearings 15 and carries a pulley 19 over which the endless belt 13 passes, in the manner clearly shown in 5 Fig. 2. At a point directly over the central portion of each tank I provide shafts 20 whose ends are rotatably mounted in bearings 21. Non-rotatably secured to each shaft 20 is a cylindrical member 22 which serves 10 as the cathode for the reception of the metals which have been ionized, all as will herein-after be fully explained. On each side of cylindrical members 22 I provide an idler 23 which is rotatably mounted on a shaft 20 15 and serves to space the surface of belt 13 away from the surface of cylinder 22, in the manner shown in Fig. 2. From Fig. 4 we notice that the idlers 23 are provided with a cylindrical face 24, on one side of which 20 there is a flange 25. The edges of the belt 13 engage the faces 24 and are guided by flanges 25.

The belt 13 consists of a piece of rubber or rubberized fabric 26, on the upper surface of which are placed a layer of transversely arranged carbon rods 27. The edges of the belt 26 are bent upwardly and then turned inwardly so as to provide a flange 28 which overlays the ends of the carbon rods 30 and serves to hold them in place all as shown in Fig. 4. In order to enable the belt to make the reverse turn, which is necessary where the belt passes from one set of idlers to another, I provide intermediate each set 35 of idlers 23 another set of idlers 29 of somewhat similar construction, but of much smaller diameter. These idlers are mounted on shafts 30 which rotate in bearings 31 secured to side pieces 1 and 2. As shown 40 clearly in Fig. 2, the belt 13 being driven from pulley 12 passes over one set of idlers 29 and is then curved downwardly by the action of idlers 23, after which it again passes over another set of idlers 29 and is 45 then curved downwardly by another set of idlers 23, etc., after which it passes from the last set of idlers 29 to pulley 19 and returns to pulley 12 by passing underneath the electrolyte tanks.

50 In order that the pulverized ore may be conveniently and evenly distributed over the carbon surface of belt 13, I provide a hopper 33 which has an inclined bottom 34 leading to an opening which can be closed by a 55 sliding door 35. A rack and pinion operated by the handwheel 36 serves to adjust the size of the opening so that the ore may be fed onto the surface of the belt at any rate desired. A motor 37 for producing the 60 power necessary to drive the machine may be attached to the bottom of the machine in the manner shown, or it may be placed on the floor or on the ceiling; in fact, the specific location is immaterial. A belt 38 or 65 other power transmitting means connects

the motor 37 with the wheel 39, which is fastened to one end of shaft 11. In order to rotate the cylindrical cathode a belt wheel 40 is secured to shaft 11 between wheel 39 and the side of the machine. A belt 41 connects pulley 40 with the inner pulley 42 on the end of the shaft 20 nearest the drive end of the machine. A second belt 43 joins the outer pulley 42 with the outer pulley 44 on the next shaft 20, and a third belt 45 extends from pulley 44 to pulley 46, while a fourth belt 47 extends from one of pulleys 46 to pulley 48 on the end of brush shaft 49, and serves to rotate brush 50 which rotates in a counter-clockwise direction when seen from the direction in which Fig. 2 is viewed. 80

From the above description it will be evident that as the machine operates, the belt will move so that its upper surface travels from the hopper 33 towards the vats 6, 7 and 8, and at the same time the cylindrical cathodes 22 rotate in a counter-clockwise direction. The ore which is deposited on the upper surface of belt 13 is carried along with the belt and passes successively through the several tanks 6, 7 and 8. Each tank contains a different electrolyte and is intended to remove a different metal or a group of similar metals. Tank 6, for example, may contain a solution of silver nitrate, tank 7 a solution of copper sulphate, and tank 8 a solution of gold potassium chloride. By means of a suitable brush 51 properly insulated from the body of the machine, and contacting with the carbon rods 27 of belt 13, the belt is connected to the positive pole of a suitable source of current, such as a low voltage direct current generator of large current capacity. Each one of shafts 20 is electrically connected to the negative pole of the source of current and becomes the cathode of the electrolytic cell. As the belt moves from right to left (Fig. 2) the ore will enter the electrolyte in tank 6, which we assume will be silver nitrate; here the silver in the ore will be ionized by the current passing from the anode to the cathode and electrolytically deposited on the specially prepared surface of the cylindrical cathode 22. From tank 6 the ore will be carried over the top of the first set of idlers 29 and down into the copper sulphate electrolyte in tank 7, where the copper will be ionized and deposited on the surface of the rotating cathode. From tank 7 the ore is carried into tank 8 which may contain gold potassium chloride, and here the gold will be ionized and deposited on the surface of the corresponding cathode. 115

The absolute separation of one metal from the other is very difficult to obtain in practice and although it is my intention to carefully adjust the current densities and voltages between the common anode and the rotatable cathode of each tank as near as 125

practicable to the theoretical values, I do not claim that I can accomplish a thorough selective separation and this is not considered essential as my object is primarily to 3 separate the metal values from the ore. It is my intention to obtain the best selective separation that is practicable and then to refine the metals deposited on the cathodes by other means.

10 I have shown only three tanks in series, but it is evident that any desired number may be employed. Since the upper surface of belt 13 is made of carbon, it is conductive, and the current will travel in the carbon surface 15 face from brush 51 to the farthest tank. If any difficulty should be experienced in conducting the current along the belt, suitable brushes may be employed at the points where the belt enters the electrolyte of each 20 tank.

The current densities of each cell may be controlled by means of rheostats in the well known manner. In Fig. 1 I have shown a generator G whose anode is connected to 25 the brush 51 by means of a suitable conductor C and whose cathode is connected to the shafts 20 of the several cathodes 22 through adjustable rheostats R. By this arrangement it becomes possible to adjust 30 the current values of each cell independently of the others. If it is found necessary or desirable I intend to avail myself of any other electrical connection and means that may be required to obtain the proper regulation.

35 After the ore has passed through all of the electrolytic cells, it will be carried to the left hand end of the machine (Figs. 1 and 2) and dumped onto a suitable conveyor (not shown) or disposed of in any suitable 40 manner. Any material adhering to the carbon rods as the belt starts on its return travel will be brushed off by means of the rotating brush 50. In order that the conductive surface of the cathode shall be 45 limited to the outer cylindrical surface of the cathode 22, I enamel all of the surfaces of the cylindrical cathode 22 except the outer periphery thereof, with an insulating enamel, and also enamel all the surfaces of 50 the idlers 23.

The electrolytes may fill the tanks to any desired level, and I have indicated the level thereof by means of a line which I have numbered 52.

55 In order that the metal which is deposited on the cathode surface shall not adhere thereto to such an extent as to make the removal thereof difficult, I subject the conductive surface 53 to a treatment which I term 60 "mercurizing." The surface is first copper-plated and made smooth by some suitable means, after which I rub the surface with a chamois skin pad containing three parts of lead carbonate and one part of mercury 65 which has been moistened with dilute hy-

drochloric acid and water, so as to form a paste. The surface 53 is then connected to the negative pole of a source of electric current, and the pad is connected to the positive pole and forms the anode for the 7 plating. The surface is then thoroughly rubbed with the pad, whereby a portion of the lead and mercury will be ionized and deposited on the cathode surface. After the cathode has been "mercurized" in the manner described, it will still be conductive, but the ionized metal which is deposited thereon will not adhere thereto as it would to the bare metal surfaces, with the result that it may be readily removed. The metal will be deposited on the cathode surfaces in the form of a closed cylinder which cannot be removed without cutting. In order to facilitate the removal of the deposited material I cut a groove transversely of the surface 53 along one element of the cylinder and fill the same with wax, as indicated by 8 54 in Fig. 7. The wax 54 being non-conductive will cause a cut or gap in the metal deposited on the cylinder so that it may 9 readily be removed. If the metal should cover the wax surface, it may be cut by means of some sharp tool.

Oftentimes the ore contains iron or other magnetic metals, and in order to obviate the necessity of separating these by electrolytic means, I provide means whereby they may be removed by electromagnetic means. In Fig. 5 I have shown how one or more of the electrolytic cells may be equipped with magnetic means, which I shall now describe. The shaft 20' is extended on each side and the projecting ends pass through openings 54 in the ends of the U-shaped magnetic core 55, which is provided with one or more magnetizing coils 56 energized by a suitable current which, for example, renders the right hand end the north pole N and the left hand end the south pole S. Shaft 20' is made in three parts and has a central section 57 of non-magnetic material such as bronze or brass. The cylindrical cathode 22' is made up of two similar pulleys 58 separated by an annular ring of non-magnetic material 59 which may be secured to the 10 edges of pulleys 58 by means of suitable dowel pins 60. The outer cylindrical surface of the cathode is copper-plated and "mercurized" as explained above, and the inner surfaces thereof are enameled with a non-conducting enamel in the manner and for the purpose above explained. When the electromagnet 55 is energized in the manner described, the two magnetic pulleys 58 will 11 become magnetized so as to form the poles of the electromagnetic separator, and the attraction of the flux passing from one pole to the other over the non-magnetic air gap 59 causes iron and other magnetic materials 115 to be removed from the pulverized ore and 120

attached to the cathode surface where they will become embedded in the metal electrolytically deposited thereon. In this manner a large amount of electrical energy which 5 would otherwise be expended in ionizing those magnetic particles will be saved. It is contemplated that only one cathode be so formed as to make it the poles of an electromagnet, but if it should be found to be necessary more of them may be thus constructed.

From the above it will be evident that I have produced an electrolytic and electromagnetic ore separator which is so constructed that the ore is fed onto an endless 10 conveyor belt having one side constructed of acid resisting electrically conductive material such as carbon, and which is electrically connected with the positive pole of a source of electric current supply whereby 15 the ore thereon becomes the anode. The conveyor belt passes successively through a series of tanks containing different electrolytes and each of which is provided with a rotating cathode so that the ore as it passes 20 through the electrolyte is subjected to the ionizing action of the electric current and is deposited on the rotating cathode from which it may be readily removed. Where 25 the ore contains a variety of different metals 30 which cannot all be removed by the use of the same electrolyte and current density, a series of tanks are provided, as shown and explained. My separator is also so constructed that the magnetic material may be 35 removed by electromagnetic means, at a less expenditure of energy than if it were electrolytically removed.

My machine, described above, is of simple 40 construction adapted for continuous operation, and is adapted to remove any kind of metals that can be electrolytically deposited on a cathode and has a large capacity for its size.

I am aware that it is not new to separate 45 the metals from ores by electro-chemical and electromagnetic means, and I do not claim to be the discoverer of this, but I believe that I have devised a new machine which possesses several marked advantages over 50 other machines of this type, chief of which is that the ore is passed automatically through a succession of electrolytic cells where the metals are separated selectively, thus making it possible to secure the best 55 results by employing the proper electrolyte and current density for each metal.

I also desire to call particular attention 60 to the method I employ in preparing the cathode surface, which makes the surface highly conductive and at the same time prevents adhesion of the electrolyte metals to the cathode surface, so that the metal can be easily stripped off the cathode. By this means a larger cathode surface can be provided for each tank than would be possible

with a stationary cathode. My strip of wax 54 is also of great value in facilitating the removal of the electrolyte metal.

Having now described my invention, what I claim is—

1. An electrolytic ore separator, comprising a plurality of electrolytic cells, a cathode in each cell, and a common anode comprising an endless belt conveyor.

2. An electrolytic ore separator, comprising a tank containing an electrolyte, a rotatable cylindrical cathode having a portion thereof submerged in said electrolyte and an anode consisting of an endless conveyor belt.

3. An electrolytic ore separator, comprising a plurality of tanks in juxtaposition, an electrolyte in each tank, a rotary cylindrical cathode having a portion of its outer cylindrical surface immersed in the electrolyte, and a common anode for said tanks consisting of an endless conveyor belt.

4. An electrolytic ore separator, comprising a plurality of tanks in juxtaposition, an electrolyte in each tank, a cylindrical cathode for each tank mounted to rotate about a horizontal axis and having a portion of the outer surface thereof in contact with the electrolyte, a common anode for all of said tanks, said anode consisting of an endless conveyor belt having a conductive ore supporting surface, means whereby said belt is caused to pass down into and through the electrolyte at a predetermined distance from the cathode surface.

5. An electrolytic ore separator, comprising a plurality of juxtaposed tanks adapted to contain a suitable electrolyte, a cylindrical cathode in each tank mounted for rotation about a horizontal axis, and having a portion of the outer surface thereof extending below the level of the electrolyte, means for rotating said cathode whereby the entire surface thereof will be active, a pair of idlers of greater diameter than the cathode and mounted concentrically therewith, and an anode consisting of an endless belt conveyor which passes through the electrolyte in all of the tanks, said conveyor being spaced from the surface of the cathode by means of said idlers.

6. An electrolytic ore separator, comprising a plurality of juxtaposed tanks adapted to contain a suitable electrolyte, a cylindrical cathode in each tank mounted for rotation about a horizontal axis, and having a portion of the outer surface thereof extending below the level of the electrolyte, means for rotating said cathode whereby the entire surface thereof will be active, an idler mounted concentrically with said cathode at each end thereof, said idlers being of greater diameter than the cathode, an anode consisting of an endless belt conveyor having the upper surface thereof formed of electro-conductive material, said anode en-

gaging the peripheries of the idlers whereby the surface thereof is spaced from the cathode surface, and means for simultaneously rotating said cathode and moving said 5 anode through the electrolytes.

7. An electrolytic ore separator, comprising a plurality of juxtaposed tanks adapted to contain a suitable electrolyte, a cylindrical cathode in each tank mounted for 10 rotation about a horizontal axis, and having a portion of the outer surface thereof extending below the level of the electrolyte, means for rotating said cathode whereby the entire surface thereof will be active, an 15 idler mounted concentrically with said cathode at each end thereof, said idlers being of greater diameter than the cathode, an anode consisting of an endless belt conveyor having the upper surface thereof formed of 20 carbon rods and the lower surface formed of a flexible non-conducting material, said anode engaging the peripheries of said idlers whereby the upper surface thereof is uniformly spaced from the cathode surface, 25 and means for simultaneously rotating said cathode and moving said anode through the electrolytes.

8. An electrolytic ore separator, comprising in combination a plurality of juxtaposed 30 tanks adapted to contain an electrolyte, a cylindrical cathode for each tank rotatably mounted on a horizontal axis, and having a portion of its outer surface submerged in the electrolyte, an anode formed of a continuous belt conveyor having its upper surface 35 formed of carbon rods and its lower surface formed of a flexible non-conductive material, means for curving said anode downwardly into the electrolyte of each 40 tank, and to space the same from the cathode surface, means between each pair of tanks to permit the anode to be bent from an upward direction to a downward direction, means for simultaneously rotating the cathode and 45 moving the anode through the electrolyte, means for depositing pulverized ore on said anode, and means for supplying an ionizing current to said anode and cathode.

9. An electrolytic ore separator, comprising in combination a plurality of juxtaposed 50 tanks adapted to contain an electrolyte, a cylindrical cathode for each tank rotatably mounted on a horizontal axis, and having a portion of its outer surface submerged in the electrolyte, an anode formed of a continuous belt conveyor having its upper surface 55 formed of carbon rods and its lower surface formed of a flexible non-conductive material, means for curving said anode downwardly into the electrolyte of each 60 tank, and to space the same from the cathode surface, means between each pair of tanks to permit the anode to be bent from an upward direction to a downward direction, means for 65 simultaneously rotating the cathode and

moving the anode through the electrolyte, means for depositing the pulverized ore on said anode, means for adjusting the tension of said anode, and means for supplying an ionizing current to said anode and cathode. 70

10. An electrolytic ore separator, comprising in combination a plurality of juxtaposed tanks adapted to contain an electrolyte, a cylindrical cathode for each tank rotatably mounted on a horizontal axis, and having a portion of its outer surface submerged in the electrolyte, an anode formed of a continuous belt conveyor having its upper surface 75 formed of carbon rods and its lower surface formed of a flexible non-conductive material, 80 means for curving said anode downwardly into the electrolyte of each tank, and to space the same from the cathode surface, means between each pair of tanks to permit the anode to be bent from an upward direction to a downward direction, means for simultaneously rotating the cathode and moving the anode through the electrolyte, 85 means for depositing pulverized ore on said anode, means for adjusting the tension on said anode, a rotating brush engaging the under surface of said anode, and means for supplying an ionizing current to said anode and cathode. 90

11. An ore separator comprising a plurality of tanks in juxtaposition, an electrolyte in each tank, a rotary cylindrical cathode for each tank, said cathodes having a portion of their outer cylindrical surface immersed in the electrolyte, a common 95 anode for all of said tanks, said anode consisting of an endless conveyor belt, and electromagnetic means for separating magnetic material and attaching the same to the 100 cathode. 105

12. An ore separator comprising a plurality of tanks in juxtaposition, an electrolyte in each tank, a rotary cylindrical cathode for each tank, said cathodes having a portion of their outer cylindrical surface immersed in the electrolyte, a common anode for all of said tanks, said anode consisting of an endless conveyor belt, means comprising 110 a magnetizing coil cooperating with the cathode for magnetizing the same, whereby magnetic material will be attracted to the cathode surface. 115

13. An ore separator comprising a plurality of tanks in juxtaposition, an electrolyte in each tank, a rotary cylindrical cathode for each tank, said cathodes having a portion of their outer cylindrical surface immersed in the electrolyte, a common anode for all of said tanks, said anode consisting of an endless conveyor belt, the cathode being formed of a pair of magnetic members spaced by an annular ring of non-magnetic material, and means for causing one of said members to form the positive pole and the other the negative pole of a magnetic cir- 120 125 130

cuit, whereby magnetic material will be attracted to the cathode surface and become embedded in the electrolytic metal.

14. An ore separator comprising a plurality of tanks in juxtaposition, an electrolyte in each tank, a rotary cylindrical cathode for each tank, said cathodes having a portion of their outer cylindrical surface immersed in the electrolyte, a common anode for all of said tanks, said anode consisting of an endless conveyor belt, said cathode being formed of a pair of axially spaced

cylindrical magnetic members, a shaft of non-magnetic material joining the central portion of the two cathodes, an annular non-magnetic ring joining the outer peripheral portions of the cathodes, shafts of magnetic material upon which said cathode members are mounted, and electromagnetic means for magnetizing said cathode parts in such a manner that each constitutes the opposite pole of a magnetic current.

In testimony whereof I affix my signature.
WILLIAM A. SHARPE.
